UNITED STATES PATENT OFFICE.

RALEIGH H. STALEY, OF SPRINGFIELD, ILLINOIS.

AUTOMATIC FORMER FOR BRICKS.

SPECIFICATION forming part of Letters Patent No. 663,688, dated December 11, 1900.

Application filed January 25, 1898. Serial No. 667,875. (No model.)

To all whom it may concern:

Be it known that I, RALEIGH H. STALEY, of Springfield, in the county of Sangamon and State of Illinois, have invented a new and Improved Automatic Former for Bricks, of which the following is a specification.

The corners of street-paving bricks often require to be rounded. My improved machine is adapted to form or shape the end corners or edges, as well as the longitudinal angles, of bricks in this fashion. Said machine is in practice arranged between the machine which forms the clay into a continuous bar and the machine which afterward divides or cuts such bar into bricks of the desired length.

In my improvement two die-wheels are arranged opposite each other, and the bar of clay passing from the brick-machine proper to the cutter is acted on not only by such die-wheels, but by dies proper arranged slidably within the latter and which are automatically projected therefrom at regular intervals by means of cams or hammers actuated by mechanism hereinafter described.

In the accompanying drawings, two sheets, Figure 1 is a central vertical section of the machine. Fig. 2 is in part a plan view and in part a horizontal section of the machine. Fig. 3, Sheet 1, is a detail section on line 3 3 of Fig. 1. Fig. 4, Sheet 2, is a detail section illustrating the coaction of the cam-wheel and wipers attached to the die-hammers. Fig. 5 is an enlarged cross-section of the rim of one of the die-wheels.

As shown in Figs. 1 and 2, two die-wheels A are arranged in the same horizontal plane, with their rims 2 separated by a space having the width of the bar of clay which passes between them to the cutting-machine, (not shown,) by which it is divided into lengths suitable to form bricks. The said die-wheels 1 are mounted on vertical shafts 3, having their bearings in the frame 4. Rotation is imparted to the die-wheels 1 from the horizontal driving-shaft 5 by means of bevel-gearing 6, arranged as shown. The clay is forced out of the mill through a die in the form of a bar having rounded longitudinal edges.

The peripheries 2 of the die-wheels 1 are concave or curved transversely, Fig. 5, so as

to guide the clay bar and preserve the round form of the longitudinal edges or angles of the same. Each wheel 1 is provided with a series (preferably four) of rectangular peripheral slots 7, Fig. 2, through each of which works a die 8, the same being in the form of an elongated block and sliding radially in a guide formed by a boss 9 on the inner side of the periphery 2. The outer ends of these slideable dies 8 have a central transverse rib or cutter 10, the adjacent portions being sloped backward upon curved lines, as shown. The inner ends of the dies 8 are slotted to adapt them for slideable connection with the free ends of retracting plate-springs 11, whose other ends are secured to the peripheries 2 of the wheels 1. These springs 11 hold the dies 8 normally retracted, and the latter are successively forced outward and projected from the die-wheels 1, as shown in Fig. 2, so as to act on the clay bar by means of wipers or hammers 12, which are arranged to work within the peripheries of the respective die-wheels. The hammers 12 are forced suddenly and automatically into contact with the dies 8 by the following-described means: Each hammer proper, 12, has a vertical shank or bar 13 arranged vertically and adapted to slide on the parallel horizontal rod 14 and shaft 15, which thus serve as guides for the same. The shaft 15 rotates in bearings in the frame-uprights 16. The rod 14 is held in such uprights 16 and secured by nuts 17 on its threaded ends. Between each such fixed upright 16 and the adjacent wiper or hammer 12 is arranged a spring 18, which is coiled about the rod 14 and whose compression and tension may be adjusted by means of nuts 19 and washers 20, applied to the rod 14, adjacent to the uprights 16. The said springs 18 are held constantly under strong tension, and hence normally tend to force the hammers 12 forward—i. e., toward each other—which is done at intervals or four times in each revolution of the die-wheels 1.

The means for holding the hammers 12 retracted and for automatically releasing them to allow delivery of a blow on the dies 8 consists, primarily, of a rotary cam-wheel 21, which is fixed vertically on the aforesaid shaft 100

15 and whose irregular periphery works at its lower side between steel wear-plates 22, that form fixed attachments of the tubular extensions or guide-arms 12^a of the hammers proper, 5 12, and slide on the rod 14, as shown.

The shaft 15 is in practice geared with the driving-shaft 5, and it will therefore be apparent that the cam-wheel 21 and die-wheels A work in unison, the former intermittently 10 pushing the hammers 12 farther apart, and thereby further compressing the springs 18, and then suddenly releasing said hammers 12 at the instant they become alined with the dies 8, so that they deliver a sudden and forcible blow on the dies, and the latter are thereby 15 driven into the clay bar, so as to form therein a transverse notch having rounded adjacent sides, as illustrated in Fig. 2.

The concave form of the peripheries 2 of 20 the die-wheels A serves to shape the longitudinal edges of the clay bar and also to prevent the clay displaced by the dies which penetrate the clay bar from swelling out the corners of the same. In other words, the clay is 25 distributed more evenly throughout the brick-bar. Thus the bricks ultimately produced are rounded at their top end edges and also along their side edges simultaneously, and the transverse notches formed in the clay bar coincide 30 with the points where the cutter subsequently acts to sever the bar into bricks.

As shown in Figs. 2 and 4, Sheet 2, the cam-wheel 21 has a series of lateral projections or cams proper which are triangular in shape 35 and whose longer inclined sides work in frictional contact with the correspondingly-inclined edges of the wipers or wear-plates 22. It is apparent the cams will gradually force 40 thereto until the wipers clear the acute angles of the cams, when they shoot inward toward the body of the cam-wheel, thereby allowing the hammers to deliver their blow on the dies 8.

45 As shown in Fig. 1, the clay bar is supported and carried between the die-wheel A by a traveling belt 23, which is in practice endless and arranged on drums or pulleys. For the purpose of supporting the belt 23 where required I employ a horizontal plate or table 24, which may be adjusted vertically, as required, to adapt it to belts of different thicknesses. The adjustment is effected by set-screws 25, which work in a bracket 26, forming an attachment of the frame 4.

55 What I claim is—

1. In a machine for forming or shaping bricks from a continuous bar of clay, the combination with the mill from which said bar is 60 forced out, of a die-wheel arranged to guide the clay bar, and having one or more slots in its periphery, and a die-block adapted to work in such slot, to act on the clay bar, and means

for forcing out the die-block at regular intervals, substantially as shown and described. 65

2. In a machine for forming or shaping bricks from a continuous bar of clay, the combination with the mill from which the said bar is forced out, of die-wheels, arranged diametrically opposite, and at a distance apart corresponding substantially to the thickness of the clay bar, and provided with radial slots, die-blocks adapted to slide in such slots, and shaped to set on the clay bar as specified, and means for automatically forcing out such die-blocks intermittently, as shown and described. 75

3. In a machine for forming or shaping bricks from a continuous bar of clay, the combination with a rotatable die-wheel, having a radially-slotted periphery, and a series of die-blocks adapted to slide in the radial slots in the periphery of such wheel, and shaped to notch the clay bar on which they act, means for normally retracting the dies, and automatic means for forcing them suddenly and intermittently outward, as the wheel rotates, 80 as shown and described.

4. In a machine for forming or shaping bricks, the combination with a die-wheel having peripheral guide-slots, of dies arranged 90 to slide therein and having a ribbed face, springs for retracting the dies, wipers or hammers arranged to act on said dies, and spring and cam mechanism for actuating the hammers, suddenly and intermittently, to cause 95 them to give a sudden blow on the dies successively, substantially as shown and described.

5. In a machine for forming or shaping bricks, the combination with a die-wheel having peripheral slots, dies working slidably therein, springs for retracting the dies, cams or hammers adapted to slide horizontally on fixed guides, springs which act on said hammers, to alternately force them apart and allow them to strike sudden blows on the dies, 105 substantially as shown and described.

6. In a machine for forming or shaping bricks, the combination with the rotary die-wheels arranged horizontally opposite each other, dies working slidably in the peripheries of the same, hammers pendent within the die-wheels and adapted to slide in a straight line toward and from each other, the parallel rod and rotary shaft arranged horizontally, 110 on which said hammers are arranged to slide, spiral springs coiled about said rod and compressed between the hammer and a fixed portion of the frame, and a cam fixed on the rotary shaft, and acting simultaneously on both 115 hammers, as shown and described.

RALEIGH H. STALEY.
